[57] CLAIM

The ornamental design for leaded glass, as shown and described.

DESCRIPTION

FIG. 1 is a perspective view of the leaded glass embodying the new design;

FIG. 2 is a top plan view thereof;

FIG. 3 is a perspective view of an alternative embodiment of the design; and,

FIG. 4 is a top plan view of the alternative embodiment shown in FIG. 3.

The bottom of the leaded glass of each embodiment shown in FIGS. 2 and 4 is identical to the top.

FIG. 1

FIG. 2

FIG. 3

FIG. 4
